DESIGN FOR A WOMAN'S PANTS

Joe Brodigan, Brooklyn, N. Y.

Application January 11, 1944, Serial No. 112,213

Term of patent 7 years

(Cl. D3—17)

To all whom it may concern:

Be it known that I, Joe Brodigan, a citizen of the United States, residing at Brooklyn, in the county of Kings and State of New York, have invented a new, original, and ornamental Design for Woman's Pants, of which the following is a specification, reference being had to the accompanying drawing, forming part thereof.

I claim:

The ornamental design for woman's pants, as shown.

JOE BRODIGAN.
